UNITED STATES PATENT OFFICE.

JONAS NORTHRUP, OF HOPEDALE, MASSACHUSETTS, ASSIGNOR TO DRAPER COMPANY,
OF HOPEDALE, MASSACHUSETTS, A CORPORATION OF MAINE.

TAKE-UP MECHANISM FOR LOOMS.

1,035,808.

Specification of Letters Patent. Patented Aug. 13, 1912.

Application filed September 25, 1911. Serial No. 651,010.

To all whom it may concern:

Be it known that I, JONAS NORTHRUP, a citizen of the United States, residing at Hopedale, in the county of Worcester and State of Massachusetts, have invented an Improvement in Take-Up Mechanisms for Looms, of which the following description, in connection with the accompanying drawings, is a specification, like letters on the drawings representing like parts.

The invention to be hereinafter described relates to looms, and more particularly to the cloth take-up mechanism and associated parts.

In the production of woven fabrics of uniform texture, it is desirable that a proper length of cloth be taken up following each pick in case filling is properly laid in the shed, but that on failure to lay filling that the take-up action be temporarily suspended in order that thin places in the cloth may be avoided. When the loom is stopped for some causes, the "loom tender" often finds it desirable or necessary to move the lay back and forth without passing through that cycle of its movement where the picking action occurs, and should the take-up be effective at such times objectionable defects are liable to occur in the cloth, as well understood by those familiar with the art. On the other hand, should the "loom tender" move the lay through that portion of its cycle wherein the shuttle is picked, it is equally desirable that the take-up be properly actuated following such pick, whether effected by hand or by the usual pick or shuttle motion. Likewise when the loom has been stopped for any cause, it may be desirable to manipulate the take-up by hand.

With these generally stated facts in mind, the aims and purposes of the present invention will best be made clear from the following description of one form of means for carrying it into practical effect, it being understood that the invention is not confined to the details of the means shown but in its true scope is defined by the claims.

In the drawings;—Figure 1 is a front elevation of a loom embodying the present invention, parts being broken away and omitted; Fig. 2 is a longitudinal section of

the loom on the line 2, Fig. 1; Fig. 3 is an enlarged sectional detail on the line 3—3, Fig. 2; Fig. 4 is a section on the line 4—4, Fig. 3; Fig. 5 is a section longitudinally of the actuating shaft on the line 5—5, Fig. 3, showing the pin moving sleeve and its mounting; and Fig. 6 is a section on the line 6—6, Fig. 5.

The loom frame, comprising uprights 1 and side frames 2, may be of any desired character suitable for supporting the operating parts, and is provided with bearings 3 for a crank shaft 4 having a crank 5 connected to the lay 6 by means, such as the pitman 7, whereby upon rotation of the crank shaft the lay has imparted thereto the usual reciprocating or back and forth motion.

At each end of the lay are the usual shuttle boxes 8 and 9, longitudinally of which the picker sticks 10 and pickers 11, respectively are adapted to be moved to throw the shuttle from one to the other box by the usual actuating means, such as the picker shaft 12, Fig. 1, operated, as usual from the picker cam 13 on the cam shaft 14 Fig. 2 through suitable connections 15, Fig. 1. Further description in detail of the picking mechanism is unnecessary, as such devices are well understood by those skilled in the art, and so far as the present invention is concerned, such mechanism may be as usual, except in such respects as may hereinafter appear.

The cam shaft 14 may be driven from any suitable or available source of power, but is herein shown as being actuated from the crank shaft 4 through the gears 16 and 17, the construction being such that said shafts may be rotated in relation to each other as two to one, that is the cam shaft 14 is caused to make one complete rotation to each two complete rotations of the crank shaft.

Mounted in suitable relation with other parts of the loom is a take-up mechanism for taking up the cloth as it is woven, a characterizing feature of which is that the actuating means therefor is in operative relation thereto for only a part of the lay movement following a pick and is there-

85

95

100

after released or freed from all control of the actuating means during the remainder of the lay movement. As well understood by those skilled in the art, the picking mechanism is actuated to throw the shuttle when the shed is opened to permit its passage, a condition which may conveniently take place during some period of the lay movement between its midway position on its 10 backward and forward reciprocations, or, as expressed technically in the art, between the top and bottom center positions of the crank on the crank shaft. Usually, though not necessarily, the action of the picking mechanism is completed and the shuttle 15 started on its picking excursion as the crank approaches or approximately reaches its back position, such as indicated by full line in Fig. 2; and the present invention contemplates that immediately thereafter the take-up plates that immediately thereafter the take-up mechanism shall be actuated to take-up the cloth and then be released or freed, so that during that part of the crank shaft movement following the release of the take-up mechanism, the lay may be freely moved 20 back and forth by the "loom tender" without corresponding actuation of the take-up mechanism, such action by the "loom tender" being frequently desirable or necessary 25 in "piecing up" or in bringing the warp threads into the same plane for other reasons, as well understood by those skilled in the art. In Fig. 2, the full line position of the crank is intended to represent arbitrarily 30 the position it occupies at or about the completion of the picking movement, and the dotted line position as that reached by the crank when the take-up for that pick has been completed, the present invention having 35 in view a release of the take-up mechanism or at about the dotted line position of the crank, so that not only may the take-up be actuated by hand after such dotted line position of the crank has been reached, but 40 that the lay may then be moved forward and back by hand without causing take-up of the cloth, all of which will appear from the following description of one form of means to the above ends.

45 Supported between suitable brackets 18 secured to the loom frame is a cloth beam 19 on which the cloth 20, Figs. 1 and 2, is wound as it is woven, said cloth beam being preferably of the character shown, described, and claimed in a prior application, Serial No. 650,208 filed Sept. 19, 1911, though it is to be understood, that so far as features of the present invention are concerned, the cloth beam may be of any desired character or construction.

50 Mounted in suitable bearings 21 supported by the loom frame is a sand or take-up roll 22 about which the cloth passes, as indicated by dotted lines in Fig. 2, a guide roller 23 supported in suitable relation to the sand or take-up roll 22, Fig. 2, as by the brackets 24, being preferably employed to cause the cloth to engage a large portion of the sand roll and thus insure proper take-up action by the said roll when it is turned clockwise, Fig. 2.

55 The shaft 25 of the sand roll has secured to one end thereof a sprocket wheel 26 about which passes the sprocket chain 27 for driving the cloth beam 19 through the friction drive device 28, and said friction device may be of any desired construction to permit the cloth beam to rotate at gradually decreased speed as the cloth roll thereon increases in diameter, and as shown, is preferably, though not of necessity, the same as disclosed in said prior application to which reference may be had.

60 At its opposite end portion the shaft 25 of the sand or take-up roll is provided with a worm wheel 29 which engages and is driven by the worm 30 suitably supported in the bracket 31 sustained by the loom frame, the construction being such that upon rotation of the worm 30, the worm 65 wheel 29 and perforce the sand or take-up roll 22, will be driven to properly take-up the cloth 20 passed above said sand or take-up roll.

65 Mounted on the shaft of the worm 30 is a pinion 32 driven by the change pinion 33 carried by the stud shaft 34, Figs. 3 and 4, said stud shaft being adjustably mounted to permit the employment of change pinions 33 of different diameters suitable to the conditions of use. Obviously, the speed of rotation of the pinion 32 and perforce that of the sand or take-up roll 22 may be varied by substitution of change pinions 33 of different diameters.

70 As hereinbefore noted the present invention contemplates operative engagement between the take-up mechanism and its actuating means to properly take-up the cloth following each pick and then release of the take-up mechanism from its actuating means, so that in case the parts of the loom be moved by hand, as for instance, if the lay be moved forward and back, no take-up of the cloth will be effected, the take-up being 75 free at such time and capable of independent hand manipulation. As one form of means to this end, the actuating shaft 35 is mounted in an inclined direction from front to rear of the loom in suitable bearings 36, 37 carried respectively by the brackets 38, 39 and is prevented from endwise movement therein by suitable collars, as 40, 41, one at each side of the bearing 36, Fig. 2. Mounted on the inclined actuating shaft 35 is a beveled pinion 42 meshing with a beveled pinion 43 of twice the number of teeth mounted on the cam shaft 14, Fig. 2, the construction being such that upon one rotation of the cam shaft the inclined actuating shaft will 80

125

130

make two revolutions, and since the cam shaft makes one rotation to two rotations of the crank shaft, it follows that the inclined actuating shaft 35 rotates in unison with the crank shaft.

The inclined actuating shaft 35 carries an actuating pin 44 at its end adjacent the train of take-up mechanism, said pin being conveniently disposed in a longitudinal recess 45 formed in said shaft and having a bent up end 46 engaged with a recess 47, Fig. 5, in a sleeve 48 rotatable with but longitudinally movable on said shaft, the construction being such, that upon movement of the sleeve to the right, Fig. 5, or toward the end of the inclined actuating shaft, the end 49 of said pin will be projected beyond the end of said shaft into the position indicated in Fig. 5, and upon movement of said sleeve to the left, the end 49 of said pin will be retracted, all for a purpose as will hereinafter appear. Arranged in co-acting relation with said actuating pin 44 is a pin wheel operatively related to the train of take-up mechanism, the planes of rotation of said pin and pin wheel being at an angle to each other, with the result, that, during a portion of the rotative movement of the pin due to rotation of the actuating shaft, said pin will engage with and actuate the pin wheel and then owing to the relation of the planes of rotation of said pin and pin wheel, they will pass out of operative engagement and the pin wheel with its connected train of take-up mechanism will be free. As a good practical embodiment of this feature of the invention the pin wheel 50 is formed on one face of or secured to the pinion 33, Fig. 4, carried by the stud shaft 34, said pin wheel and pinion having their hub portions 51 supported directly by the sleeve or bushing 52, Fig. 4 having a shoulder 53 against which one end of the hub 51 may bear. The sleeve or bushing 52 extends beyond the face 54 of the pinion 33 and is mounted on the stud shaft 34, the latter passing through the slot 55 of the curved bracket 56 secured to the loom frame and having the head 57. A nut 58 and washer 59 are provided for the outer end of the stud shaft, the construction being such that by loosening the nut 58, the stud shaft, pinion 33, pin wheel 50 and sleeve or bushing 52, may be adjusted in the curved slot 55 of the bracket 56 to suit the size of pinion 33 employed for actuation of the pinion 32 and sand or take-up roll; and by tightening said nut the parts may be secured in desired adjusted position with the teeth of the pin wheel in position to be engaged by the end 49 of the actuating pin 44.

Details of the described embodiment of the invention may be obviously changed without departing from the characterizing features thereof, but the form of parts de-

scribed has been found mechanically well adapted to the purpose of the invention.

It will be noted that in the form and relation of actuating pin and pin wheel, the latter is disposed to rotate in a plane parallel to the plane of the connected pinion 33, while the plane of rotation of the pin is inclined thereto, though obviously the desired relation might be otherwise secured, whereby, as the pin rotates under the demands of the actuating shaft, it will engage the pin wheel and turn it for a portion of its path of rotation and then the pin will pass from engagement with the pin wheel, leaving it and perform the take-up mechanism free and subject to hand manipulation. Since, also, the inclined actuating shaft is caused to rotate in unison with the crank shaft, the actuating pin 44 is so disposed that when the crank shaft reaches the full line position, Fig. 2, the picking action having at or about at that time been completed, said pin will be engaged with and will actuate the pin wheel to cause take-up of the cloth, until, when the crank 5 reaches about the position shown by dotted lines, Fig. 2, the pin will pass from engagement with the pin wheel and leave it and the connected take-up mechanism free. Thus should the loom be stopped at any time, the attendant may freely move the lay back and forth by hand throughout its full cycle of operation without causing actuation of the take-up mechanism, except at that portion of the cycle indicated between the full and dotted line position of the crank in Fig. 2, such capacity being inherent in the take-up actuating means without additional parts. Likewise the attendant may at such times freely manipulate the take-up by hand without disengaging or adjusting any of the parts.

In order to restrain accidental movement of the take-up either to let back or wind up the cloth during the time the take-up is disconnected from its actuating means, the sleeve or bushing 52 is provided with an arm 60, Fig. 4, having a spring restraining finger 61 for engaging the pin wheel, or other part connected to the take-up mechanism.

When filling fails some looms are stopped, while others automatically supply fresh filling without stopping. In either event it is desirable that the take-up be arrested until take-up of the cloth is dictated by filling being properly laid in the shed.

In the present embodiment of the invention, a loom is illustrated having filling replenishing mechanism which may be of any usual or desired character, and means are provided to arrest the take-up when the filling is to be changed.

Mounted in suitable brackets 62 secured to the breast beam of the loom, Fig. 1, is the transverse shaft 63 having an arm 64 for actuating or moving a dog 65 into the

path of a suitable bunter carried by the lay 6, when the transferrer 66 of any usual type well known in the art, is to transfer a filling carrier 67 from the hopper 68 to the shuttle 5 in the box beneath. The transferrer and associated means for transferring a filling carrier from the hopper to the shuttle are or may be of well known type, and need not be specifically described herein.

10 Connected to the transverse shaft 63 is an arm 69 adapted to be moved to turn the shaft 63 clockwise, Fig. 2, when the indicating means 70, of any desired or well known construction, indicates absence of filling on 15 a detecting pick, and said parts being of well understood construction and operation to those skilled in the art, need not be specifically described, the general construction being such that should the shuttle fail to lay 20 filling on any detecting pick, the indicating mechanism 70 will be actuated by the weft hammer 71 to move the arm 69 to the right, Fig. 2, turn the shaft 63, and position the dog 65 of the transferring mechanism, so 25 that upon the next beat up movement of the lay, change of filling will occur.

Secured to and extending downward from the transverse shaft 63 is an arm 72, Fig. 2, the lower end of which engages between the 30 collars 73 and 74 formed on or secured to the sleeve 48, which for identification may be known as the release sleeve. Between the collar 73 and the bearing 37, Fig. 2, is a spring 75 acting normally to move and hold the release sleeve 48 toward the outer end 35 of the inclined actuating shaft so that the pin 44 may have its end 49 engaged with the pin wheel in the manner heretofore explained.

40 From the construction described it will be noted that when the transverse shaft 63 is rocked clockwise, Fig. 2, on the occurrence of a filling fault in the manner stated and filling is to be changed, the arm 72 will 45 also be moved to force the release sleeve 48 to the left, Fig. 2, against the stress of the spring 75 to thereby carry the end of the pin 44 out of operative position with respect to the pin wheel; and when upon replenishment of filling, the filling is properly laid 50 in the shed, the spring 75 will move the release sleeve to the right to bring the end 49 of the pin 44 into operative relation with the pin wheel. It will therefore be noted 55 that when filling is to be changed the take-up is released from its actuating means but upon successful replenishment and filling being subsequently laid in the shed, the take-up mechanism and its actuating means are 60 again restored to operative relation.

What is claimed is;—

1. In a loom, the combination of the lay, picking mechanism and its actuating means, take-up mechanism, and means acting to operate the take-up mechanism after the action

of the picking mechanism and then free the take-up mechanism to movement in either direction on every cycle of loom operation.

2. In a loom, the combination of the lay, a crank shaft for operating the lay, take-up mechanism, and means operating the take-up mechanism during a portion of each crank shaft movement and then freeing the take-up mechanism for movement in either direction on every cycle of loom operation 70 during the remainder of the crank shaft movement.

3. In a loom, the combination of the lay, picking mechanism and its actuating means, take-up mechanism, means acting to operate 80 the take-up mechanism after the action of the picking mechanism and then to be operatively disengaged therefrom to free the take-up mechanism, and means to also automatically disengage the actuating means 85 from the take-up mechanism upon or at failure of filling.

4. In a loom, the combination of the lay and its actuating means, a take-up mechanism, means including rotating parts adapted to engage for actuating the take-up and then to automatically separate after each pick to free the take-up after each take-up movement.

5. In a loom, the combination of a lay, 95 its operating crank shaft, take-up mechanism, picking mechanism, rotating means adapted to be operatively engaged to actuate the take-up mechanism while the crank shaft is in back position between top and bottom of its movement and then to disengage and free the take-up mechanism for the remainder of crank shaft movement.

6. In a loom, the combination of take-up mechanism, actuating means therefor including a pin wheel and pin carrying shaft, a lay, means for imparting a complete rotation of said pin carrying shaft for each complete cycle of lay movement to impart take-up action to the take-up mechanism and 105 then leave the take-up mechanism free.

7. In a loom, the combination of take-up mechanism, actuating means therefor including a pin wheel and pin, detector mechanism to detect the absence of filling, and means 115 actuated by or through absence of filling to place the pin wheel and pin into inoperative relation.

8. In a loom, a lay, take-up mechanism, actuating means for said take-up mechanism 120 including a pin wheel and pin, a shaft for operating the pin, and means operated to separate the pin wheel and pin by or through absence of filling.

9. In a loom, a lay, take-up roll, a pin 125 wheel in operative relation with the take-up roll, a shaft, a pin carried by said shaft to operate the pin wheel and effect take-up, a release device for moving said pin out of operative relation with the pin wheel, and 130

means operated by or through failure of filling for moving said release device.

10. In a loom, the combination of a lay, take-up mechanism, means including a pin wheel and its actuating pin for operating the take-up mechanism, said pin wheel and pin being constructed and arranged to be engaged directly after the action of the picking mechanism, and then to pass out of operative engagement to free the take-up mechanism to hand manipulation.

11. In a loom, the combination of take-up mechanism, and means for actuating said mechanism, said means including two rotary devices rotating in planes inclined to each other and adapted for operative engagement for a part only of the rotary movement of one of said members.

12. In a loom, the combination of take-up mechanism, a pin wheel in operative relation therewith, an actuating shaft, an actuating pin operated by said shaft in a circular path at an angle to the plane of the pin wheel, and means for operating said shaft.

13. In a loom, the combination of a lay, a crank shaft for operating the lay, picking mechanism, take-up mechanism, an actuator for said take-up mechanism operating to take up the cloth when the crank shaft is in back position between top and bottom of its movement and then to free the take-up mechanism for the remainder of the crank shaft movement.

14. In a loom, the combination of a lay, a crank shaft for operating the lay, picking mechanism, take-up mechanism, an actuator for said take-up mechanism operating to take up the cloth when the crank shaft is in back position between top and bottom of its movement and then to free the take-up mechanism for the remainder

of the crank shaft movement and means to retard accidental movement of the take-up mechanism when freed from its actuator.

15. In a loom, the combination of filling 45 replenishing mechanism, take-up mechanism, two rotary devices rotatable in paths inclined to each other for actuating the take-up mechanism by engagement of said devices during a part of the rotary movement 50 of one of them, and means for relatively moving said two rotary devices into inoperative relation when the filling is to be changed.

16. In a loom, the combination of take-up mechanism, the lay, a crank shaft for operating the latter, an inclined actuating shaft for the take-up mechanism rotating in unison with the crank shaft picking mechanism, and means carried by said actuating 60 shaft for actuating the take-up mechanism directly following the picking action and then freeing the take-up mechanism when the crank of the crank shaft is in the lower part of its movement.

17. In a loom, the combination of a lay, a crank shaft for operating the lay, a take-up mechanism, an actuator for said take-up mechanism comprising a wheel, a rotary operating device for actuating said wheel 70 when the crank shaft is in back position, continued rotary movement of said device in the same direction thereafter freeing said wheel and take-up mechanism for the remainder of the crank shaft movement. 75

In testimony whereof, I have signed my name to this specification, in the presence of two subscribing witnesses.

JONAS NORTHROP.
